RUTH FELLS, OF BROOKLYN, NEW YORK, ASSIGNOR TO UNITED STATES MAIL CHUTE CORPORATION, OF NEW YORK, N. Y., A CORPORATION OF NEW YORK

MAIL CHUTE

Application filed September 7, 1929. Serial No. 390,873.

This invention relates to a mail chute or conduit for conveying letters and other like mail matter from the several floors of a building to a receptacle therefor in the first floor, 5 or basement, or other place. In installing mail chutes in a building it is necessary, as will be readily understood, to place the chute in an absolutely upright or vertical position. Due, however, to the unevenness or irregular- 10 ity of the walls, at least in some buildings, difficulty is often experienced in aligning the parts of the chute to make them vertical. In the construction of mail chutes it is also customary to employ a plurality of channel mem- 15 bers each fitted with a wall or panel, the panels preferably being removably connected to their respective channel members. These panel members are customarily provided with a frame which fits over the edge portions 20 of the channels. Consequently in ordinary constructions there is no provision made against indenting or depressing the sides of the channel. It is obviously of much importance to so construct and connect these parts, 25 that is, the channels and their panels, that under ordinary conditions it is impossible to indent or depress the side members of the channels.

Now the objects of my invention are to 30 overcome these difficulties and in so doing to employ a simply constructed mechanism by which the parts of the mail chute may be aligned and installed in a vertical position and also to employ a frame member as a part 35 of each panel and adapted to receive an edge portion of the side of a channel member to maintain the same in position. It will be understood, of course, that while these devices are particularly adapted to be employed in 40 conjunction with mail chutes their use is not so specifically limited as they may be employed in aligning other devices in a vertical position and also for maintaining the side walls of divers structures in place.

In the drawings Figure 1 is a transverse 45 sectional plan illustrating a mail chute structure in which my invention is embodied,

Fig. 2 is a sectional elevation on line 2—2,

Fig. 1,

Fig. 3 is a sectional plan on an enlarged

scale illustrating the construction of the frame of a panel,

Fig. 4 is a partial sectional plan showing the adjustable attaching devices connected directly between the wall and a part of the 55 conduit or chute, and

Fig. 5 is a sectional elevation showing another form of the invention.

In the drawings 10 designates a part of a wall. In carrying out the invention I employ angle irons 11 and 12, the corresponding legs of which are placed against the wall 10 and secured in position by means of screws 13 and 14, or otherwise. The outer face of the other leg of the angle iron 11 is provided 60 with a series of teeth or serrations 15 and in this leg of the angle iron there is a slot 16. In the corresponding face of the leg of the angle iron 12 there is a series of teeth or serrations 17 and this leg of the angle iron is 65 provided with a slot 18. Associated with the outer leg of the angle iron 11 there is an angle iron 19 and associated with the angle iron 12 there is an angle iron 20.

The inner face of one of the legs of the angle iron 19 is provided with a series of teeth or serrations 21 adapted to interengage with the teeth or serrations 15 in the angle iron 11 and these angle irons are adapted to be adjustably placed and connected relatively 70 to each other by means of a suitable screw 22 passing through the slot 16 and turned down into a tapped opening provided therefor in the serrated leg of the angle iron 19. In a similar manner one leg of the angle iron 20 75 is provided with a series of teeth or serrations 23 adapted to interengage with the teeth or serrations 17 in the angle iron 12, and these angle irons are adapted to be adjustably placed and connected relatively to each other 80 by a suitable screw 24 passing through the slot 18 and turned down into a tapped opening provided therefor in the serrated leg of the angle iron 20.

Associated with each of these sets of angle 85 irons I employ an additional angle iron. As illustrated an angle iron 25 is associated with the angle irons 11 and 19 and an angle iron 26 with the angle irons 12 and 20. In one leg of the angle iron 25 there is a slot 27. 100

Passing through this slot there is a screw 28 adapted to be turned down into a tapped opening provided therefor in the adjacent leg of the angle iron 19. In a similar manner 5 in one leg of the angle iron 26 there is a slot 29. Passing through this slot 29 there is a screw 30 adapted to be turned down into a tapped opening provided therefor in the adjacent leg of the angle iron 20. In this 10 manner the angle iron 19 may be adjustably connected to the angle iron 25 and the angle iron 20 to the angle iron 26. The unslotted legs of the angle irons 25 and 26 are adapted to extend over the adjacent sides of the angle 15 irons with which they are associated.

The slotted legs of the angle irons 25 and 26 are connected to the back member 31 of the band by being welded thereto, or by means of suitable screws, as indicated at 32 and 33. 20 In either event this back member 31 of the band is provided with openings 34 and 35 through which, as will be understood, the heads of the screws 28 and 30 are accessible.

Together with a back member 31 the band 25 member may include side members 36 and 37 and a front member 38. The front member 38 as illustrated is pivotally connected, as at 39, to the forward end of the side member 36 and at its opposite end this front member 30 is fitted with a lock bar 40 which is pivotally connected thereto, as indicated at 41. With the parts in position the lock bar 40 is adapted to lie against the outer face of the side member 37 and the parts maintained in this relationship by means of a suitable lock 42 or otherwise. The front member 38 may include an offset lower portion 43 between which and its upper portion there is provided a letter slot 44. Associated with the 40 band and held in place thereby are the usual channel members preferably formed of sheet metal. Two of these are shown in the drawing and at their overlapping ends, as is customary, are made to lie within the band. 45 The back of the upper channel member is indicated at 45 and the sides thereof at 46 and 47. The back of the lower channel member is indicated at 48 and the sides thereof at 49 and 50.

50 As hereinbefore described the adjustable devices for aligning the parts of the chute are arranged between the wall and the band employed at the joint between the channels of the chute in which band, as is customary, the 55 opening or slot for the admission of letters or other matter to be mailed, is provided. It is customary and, of course, necessary to employ one of these bands on each floor. In some instances the alignment of the parts of the chute 60 may be accomplished in this manner, that is, by merely applying the adjusting devices to the band and connecting the same to the wall. In other instances, however, it may be necessary or advisable to connect the channel members of the chute directly to the wall and to

apply the band member to the channel members and their panels in the customary manner. In such instances, furthermore, it may be necessary to employ one, or two, or more, of the sets of adjusting devices on each floor in order to properly align the parts of the chute. 70 In Fig. 4 I have illustrated the connection of the channel members directly to the wall by means of the same type of adjusting devices as those hereinbefore described. In this figure, however, the adjusting device at one side of the channel only is illustrated, it being understood that the adjusting device at the other side of the channel is a duplicate thereof. In this structure the angle iron 25 is, for instance, connected directly to the back 45 of the upper channel member. This may be effected by welding the parts together or otherwise. The angle iron 19 is adjustably connected to the angle iron 25 by the screw 28, the head of which lies within the countersunk portion of the slot 27 while the shank of the screw passes through the slot and into the tapped opening in the adjacent leg of the angle iron 19. The angle iron 11 in this instance is connected to the wall 10 in the same manner as hereinbefore described and the angle iron 19 is adjustably connected to the angle iron 11 by means of the screw 22 passing through the slot 16 by being turned down into a tapped opening provided therefor in the adjacent leg of the angle iron 19. As hereinbefore stated this type of adjusting device may be employed with either, or both, or any number of channels and any necessary number of the sets of adjusting devices may be employed with any one channel in order to effect the desired result of installing the conduit in such a manner that it will assume a vertical position. 90

As is customary each of these channel members is fitted with a removable panel. Each removable panel preferably comprises a plate of glass or other transparent material and a metal frame adapted to cover or otherwise engage the edge portions of the side members of the corresponding channel. As illustrated the glass plate of the upper panel is indicated at 51 and the frame with which this glass plate is fitted is preferably made of sheet metal and so formed as to include a side 52 having walls 53 and 54, together with a front member 55 and a base 56. The edge portion of the plate glass 51 is yieldingly maintained in position between the edges of the front member 55 and the base 56. The wall 54 which terminates in the base 56 is so constructed as to include a loop 57 with a space 58 between the parts of the loop and adapted to receive the outer or free edge of the side of the channel with which the panel is associated. This is clearly illustrated in Fig. 1 wherein, for example, the side member of the frame of the panel fits over the side wall 46 and the edge of the side wall 46 fits into the space 58. Ob- 100

viously the structure is the same on both sides of the panel. The glass plate of the lower panel is indicated at 59 and it will be understood that this is fitted with a frame 60 having the sides thereof constructed in the same manner as those hereinbefore described for the upper panel.

It is to be understood and noted that wall 54 and the short extension of the base 56, 10 which are adapted to form the loop 57 with the space 58 to receive the outer or free edge of the channel with which the panel is associated, has an additional function in that the long arm 54 forming one side of the 15 socket serves as a guide for the end walls 46 and 47 of the channel or a guide for the panel in its movement towards the end walls of the channel so that, as the panel is moved towards the channel the long arm 54 of the 20 socket contacts with the outer surface of the side walls 46 and 47, causing the free ends thereof to be directed into the space 58, that is, the socket formed by the loop 57.

In some instances, as will appear by reference to Fig. 5, the angle irons 12 and 20 25 may be connected in the usual manner and a single bolt 61 used for securing these connected angle irons to the wall and to the band, or to the wall of the channel, the head 30 of the bolt or screw 61 lying in the countersunk slot 35 in the angle 26 and passing through the angle iron 20 and also through the angle iron 12 and into the wall so as to 35 secure the parts together and maintain them in position for use.

It will now be understood that in the use of the improvements hereinbefore described in the installation of mail chutes the irregularities which there may be in the wall against 40 which the mail chute is to be placed cause little or no difficulty in placing the chute in an upright or vertical position, this difficulty being overcome by such adjustment of the sets of angle irons 11 and 19 and 12 and 20 45 as may be necessary. It will also be apparent in the use of removable panels fitted with the type of frame hereinbefore described that it is substantially impossible for the side members of the channels to be bent or 50 moved inwardly due to the edge portions thereof being located within and held in position by the sockets provided for this purpose in the inner wall and the base of the frames of the panels. Obviously also, the 55 improvements hereinbefore set forth are not specifically limited to the purposes specified as they may be employed to advantage in other constructions without departing from the nature or spirit of the invention.

60 I claim as my invention:

1. In a mail chute, a conduit, sets of angle irons for connecting the conduit to a wall, each set of angle irons comprising a member connected to the wall, a member connected to 65 the chute, and an intermediate member ad-

justably secured to the member connected to the wall in order to insure the position of the chute being vertical irrespective of irregularities in the surface of the wall.

2. In a mail chute, a conduit, and sets of angle irons for securing the conduit to a wall, each set of angle irons comprising a member to be connected to the wall, a member connected to the conduit and an intermediate member adjustably connected to both the aforesaid members in order to cause the conduit to assume a vertical position irrespective of irregularities in the surface of the wall.

3. In a mail chute, a conduit, and sets of devices for connecting the conduit to a wall, each set of devices including an angle iron adapted to be secured to the wall, an angle iron secured to the conduit and an intermediate angle iron adjustably connected to the angle iron to be secured to the wall and also adjustably connected to the angle iron secured to the conduit.

4. In a mail chute, a conduit, sets of devices for securing the conduit to a wall, each set of devices comprising an angle iron to be connected to the wall, an angle iron connected to the conduit and an intermediate angle iron, means for adjustably connecting the angle iron secured to the conduit to the intermediate angle iron, and means for adjustably connecting the intermediate angle iron to the angle iron to be secured to the wall.

5. In a device of the class described, a channel member having back and side portions, and a panel member comprising a glass plate and resilient frames therefor extending along the sides thereof, the free edges of said resilient frames being adapted to embrace the opposite faces adjacent the edges of the sides of said glass plate, there being formed along the length of the resilient frames intermediate the edges thereof, resilient walled sockets adapted to receive the edges of the respective side portions of said channel member, the walls of said sockets being spaced apart a distance equal to the thickness of the side portions of the channel member, whereby, upon pressing the panel member against the channel member, the edges of the side portions of said channel member may be guided into and become operably retained within the sockets of the resilient frames.

6. In a device of the class described, a channel member having back and side portions, and a panel member comprising a glass plate and resilient frames therefor extending along the sides thereof, the free edges of said resilient frames being adapted to embrace the opposite faces adjacent the edges of the sides of said glass plate, there being provided in the resilient frames intermediate the edges thereof U-shaped resilient walled sockets adapted to receive the edges of the respective side portions of said channel member, the walls of said sockets being spaced apart a distance

- equal to the thickness of the side portions of the channel member, the walls of said sockets being respectively long and short, whereby, upon pressure of the panel member against the channel member, the edges of the side portions of the channel member may contact with the longer walls of the sockets and be guided into said sockets to become operably interlocked with the resilient frames.
7. In a device of the class described, a channel member having back and side portions and a panel member comprising a glass plate and resilient frame sections cooperating with the sides of said glass plate, said resilient frame sections being bent over on themselves intermediate the edges thereof to form sockets adapted to receive the respective side portions of said channel member, the free edges of said resilient frame sections being overturned laterally to embrace opposite faces adjacent the edges of the sides of the glass plate, the walls of said sockets being spaced apart a distance equal to the thickness of the side portions of the channel member, whereby, upon pressing the panel member against the channel member the edges of the side portions of the channel member may be guided into and become operably retained within the sockets of the resilient frames,
8. In a device of the class described, a channel member having back and side portions, and a panel member comprising a glass plate and resilient frame sections cooperating with the sides of said glass plate, said resilient frame sections being bent over on themselves intermediate the edges thereof to form sockets, the walls of which are spaced apart a sufficient distance one from the other to receive the respective side portions of said channel member, the free edges of said resilient frame sections being overturned laterally to embrace the opposite faces adjacent the edges of the sides of the glass plate, whereby, upon pressing the panel member against the channel member, the edges of the side portions of the channel member may be guided into and become operably retained within the sockets of the resilient frames.
9. In a device of the class described, a channel member having back and side portions and a panel member comprising a glass plate and resilient frames therefor, extending along the sides thereof, the free edges of said resilient frames being adapted to embrace the opposite faces adjacent the edges of the sides of said glass plate, there being formed along the length of the resilient frames, intermediate the edges thereof, resilient walled sockets, the walls of which are spaced apart one from the other a distance sufficient to receive the edges of the respective side portions of said channel member, whereby, upon pressing the panel member against the channel member, the edges of the side portions of said channel

member may be guided into and become operably retained within the sockets of the resilient frames.

Signed by me this 9th day of August, 1929.
